HIGH-FREQUENCY TERMINATING
IMPEDANCE

William W. Hansen, Garden City, N. Y., assignor
to The Sperry Corporation, a corporation of
Delaware

Application July 30, 1943, Serial No. 496,715

5 Claims. (Cl. 178—44)

1

The present invention is related to the art including high frequency energy conducting systems and it is more specifically related to devices for providing an energy sink or energy-absorbing termination for concentric transmission lines.

As the frequencies utilized in radio communication and radio control have increased, it has become necessary to use substantially enclosed, non-radiating energy conductors such as the well known concentric transmission line type. In many types of application of such energy conducting devices, it is necessary to provide a termination for the conductor which will avoid the production of reflected electromagnetic waves in the energy conducting system. Such reflected waves, of course, combine with the forward traveling energy and produce so-called "standing waves" which interfere with the proper functioning of other portions of the system by rendering the apparatus position sensitive; that is, the effects produced may depend upon the position at which the particular apparatus in question is connected to the energy conducting system. In addition, the power transfer through the system may be materially reduced. It is desirable, therefore, to provide a terminating device which will be able to absorb whatever energy is flowing through the system without producing reflections or standing waves. Such terminating devices are also known as energy sinks or black bodies, since they absorb substantially all energy incident thereon without retransmitting an appreciable amount of such energy.

Accordingly, it is an object of the present invention to provide an improved form of terminating device for high frequency energy conducting systems.

It is a further object of the present invention to provide an improved high frequency terminating device for concentric transmission lines adapted to properly terminate such lines substantially without reflection or standing waves.

It is another object of the present invention to provide a practical and easily manufacturable form of such high frequency terminating devices.

It is still another object of the present invention to provide an improved form of concentric line terminating device which is substantially insensitive to variations in frequency and there-

2

fore may be utilized with a large number of widely varying operating frequencies.

It is a further object of the present invention to provide an improved form of energy sink or terminating device adapted for use at high power.

Other objects and advantages will become apparent from the following specification and attached drawings in which

Fig. 1 shows a longitudinal cross-sectional view of one form of the present invention.

Fig. 2 shows a similar longitudinal cross-sectional view of a more practical embodiment of the present invention adapted for easy manufacture, and

Figs. 3 and 4 show similar views of other forms of my invention.

As is well known, a suitable terminating device for a concentric transmission line must provide a substantially pure resistance equal to the characteristic impedance Z_0 of the transmission line to be terminated. However, if an ordinary lumped resistance is inserted in the end of such a transmission line it will be found that, at the high frequencies with which such devices are used, the terminating resistance also usually displays a reactance which prevents matching of the device to the line. Also, with lumped high frequency resistances usually employed, it may be so small as to have limited power handling capabilities.

According to the present invention, a terminating impedance is provided which presents a substantially pure resistance so that matching to the line is effected without frequency dependency and which can handle appreciable amounts of power. In the present instance, as seen in Fig. 1, the concentric transmission line to be terminated is represented by the outer conductor 11

and the inner conductor 12. Joined to the inner conductor 12 is a rod 13 of resistance material having a diameter substantially the same as that of inner conductor 12 and forming a smooth continuation thereof.

The length of rod 13 is so chosen with relation to the resistivity thereof that the total resistance of the rod is equal to the characteristic impedance of the line, that is, $Z_0 = rL$, where r is the resistance per unit length of the rod 13 and L is the length of the rod. To complete the

terminating impedance, rod 13 is surrounded by a conducting member 14 which has an inner taper 16 of an exponential character, which will be shown more clearly below.

Thus, by the well known transmission line equations, the current and voltage relations at any point x along the tapered line of Fig. 1 may be written:

$$\frac{di}{dx} = jcv \quad (1)$$

$$\frac{dv}{dx} = (r + j\omega l)i \quad (2)$$

where i is the current, v is the voltage, c is the unit capacitance, l is the unit inductance, ω is the radian frequency, and j is the pure imaginary $\sqrt{-1}$. If it be assumed that

$$i = Ae^{jkx} \quad (3)$$

where A is a constant, e is the base of the Napierian logarithm, and k is a constant to be determined, then Equation 1 becomes

$$jkAe^{jkx} = jcv$$

or

$$v = \frac{k}{c\omega} Ae^{jkx} \quad (4)$$

and

$$\frac{v}{i} = \frac{k}{c\omega} \quad (5)$$

Thus, Equation 5 indicates that, at point x , the ratio of voltage to current will be real if R is real, and will be independent of frequency if k is a multiple of ω . By selecting $k = \omega l$ these conditions are satisfied, and then

$$Z = \frac{k}{c\omega} = \frac{\omega l}{c\omega} \quad (6)$$

is the characteristic impedance at x .

Substituting (4) and (6) in (2),

$$\frac{dv}{dx} = Ae^{jkx} \frac{dZ}{dx} + jkZAe^{jkx} = (r + j\omega l)Ae^{jkx} \quad (7)$$

By equating the real components of (7),

$$\frac{dZ}{dx} = r \quad (8)$$

and therefore $Z = rx$.

If the line 11, 12 has a characteristic impedance Z_0 , then rL is chosen equal to Z_0 , and the device will serve as a proper frequency-independent termination.

As is well known, the characteristic impedance Z_0 of a concentric transmission line such as 11, 12 may be given by the following expression:

$$Z_0 = 60 \log \frac{b_0}{a} \quad (9)$$

where b_0 is the radius of the outer conductor of the line 11, 12 and a is the radius of the inner conductor thereof. For a tapering or varying line such as 13, 14, the corresponding expression, which may be termed the characteristic impedance Z at a point of the line section, will depend upon the position considered along the line. If we let the variable x represent the distance from the closed end of the device, as shown in the diagram, to a point along the line being considered, and if b_x is the radius of the outer conductor at that point, then

$$Z = 60 \log \frac{b_x}{a} \quad (10)$$

However, Z should also equal

$$xr = Z_0 \frac{x}{L}$$

as shown above at (8).

Equating these last two expressions, we derive the expression

$$b_x = ae^{\frac{rx}{L}}$$

which, as it seen, represents a pure exponential variation for the curvature 16 of the outer conductor 14 with respect to x .

With this relation it can be shown that the power dissipated per unit length of the terminating impedance is constant and equal to

$$\frac{1}{2} r I_0^2$$

where I_0 is the maximum value of current flowing in the inner conductor, which can also be seen from (3) to have constant magnitude but variable phase along the terminating impedance device.

Furthermore, as shown above, the impedance offered by the present terminating device is entirely independent of frequency, as is the characteristic impedance Z_0 ; that is, this terminating impedance is substantially a pure resistance. Accordingly the present device can be utilized for widely varying operating frequencies while still maintaining substantially perfect impedance matching and the optimum energy dissipating characteristics produced by the constant power dissipation along the length of the device.

The device of Fig. 1 is somewhat difficult to manufacture in view of the requirement that the inner taper of conductor 14 must be a substantially perfect exponential curve. However, a device can be produced which performs substantially in the same manner as that of Fig. 1, which is relatively easy to fabricate. Such a device is shown in Fig. 2 in which the outer conductor 14 is formed as a series of steps, preferably, each step being short compared to one wave length at an operating frequency in the center of the operating range of frequencies. Preferably these sections may be one-eighth wave length or less in length. These sections are made to approximate the exponential curve of Fig. 1 by choosing a constant ratio for the diameters of the successive sections, making the characteristic impedances vary substantially linearly along the device. The change in characteristic impedance from section to section is then constant.

By making the number of sections relatively large, the device is rendered quite insensitive to variations in the operating frequencies from the optimum value. With this relation among the characteristic impedances of the several sections, the over-all effect of all the sections is substantially the same as the exponential curve variation of Fig. 1.

It will be noticed that the device of Fig. 2 can be manufactured by relatively simple machining or drilling operations. The center conductor may be held in place by suitable set screw 17 or may be pressed into the end of the outer conductor 14 or fixed in any other desired manner. The other end of the resistive conductor 13 may be suitably supported by the inner conductor 12, as by means of a suitable conducting peg arrangement illustrated at 18 or in any other manner.

It will be understood that center conductor 12 is supported within conductor 11 by the usual insulating spacers or stub lines.

The inner conductor 13 may be formed as a solid rod or hollow cylinder of the proper resistivity, or may be formed as a resistance coating on an insulating form or rod.

While the above forms of the invention have been illustrated with the resistance incorporated in the inner member and the taper in the outer member, it is to be understood that these features may be reversed. Thus, in Fig. 3 a similar terminating impedance is illustrated in which the inner conductor is tapered and the outer conductor is uniform. As seen above, the essential criterion for the terminating device of the invention is that the characteristic impedance of the terminating device vary linearly from the value Z_0 characteristic of the line 11-12 to the value zero. For this purpose the ratio of the outer conductor diameter to the inner conductor diameter must vary exponentially.

In the device of Fig. 1, this exponential relation was obtained by a constant inner conductor and an exponentially varying outer conductor. In the device of Fig. 3, this relationship is obtained by a constant outer conductor diameter and varying inner conductor diameter. The essential relationship is defined by the following equation,

$$60 \log \frac{b}{a_x} = xr \quad (11)$$

from which is obtained the equation

$$a_x = be^{\frac{-xr}{60}} \quad (12)$$

which indicates how the radius of the inner conductor must vary to provide the desired impedance relation.

In the device of Fig. 3, the outer conductor 14" is preferably made of resistance material or may have a surface coated with resistance material. The inner conductor 13" is preferably made of conductive material so that substantially all of the resistivity of the tapered line is produced by the outer conductor, the resistance of the inner conductor being negligible with respect thereto.

This device of Fig. 3 has an advantage over that of Fig. 1 in that the inner conductor 13" may be manufactured by a relatively simple machining operation, as by turning on a lathe. Also, the much larger area of the resistive element 14" and its location at the outside of the device permits better heat dissipation and use in higher power systems.

The device of Fig. 3 may be approximated in a manner similar to that shown in Fig. 2 by use of short stepped sections. This is shown in Fig. 4 where the inner conductor 13" is now formed of stepped sections such that the ratio of the radii of successive sections remains constant. The length of the sections is again preferably less than one-eighth wave length. Here again, the outer conductor 14" is made the resistance member of the device.

The device of Fig. 4 is still more readily adapted for manufacture, since it is relatively simple to assure accurate machining of externally formed

cylindrical sections of member 13" while the accurate machining of an exponential taper, as in Fig. 3 or Fig. 1, is relatively difficult.

Accordingly, I have provided a terminating impedance for a concentric transmission line which provides proper termination over a wide range of frequencies, which provides a desired uniform distribution of the power dissipation to avoid overheating of any local area, and which is relatively simple to manufacture and assemble.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

20. 1. A high frequency terminating impedance comprising a section of concentric transmission line having a resistive inner conductor of uniform diameter and constant resistance per unit length, and an outer conductor formed of a series of sections, each section having a constant inner diameter and a ratio of the diameters of successive sections being constant.
25. 2. A high frequency terminating impedance as in claim 1, wherein each of said sections has a length which is less than one-eighth wave length at the operating frequency thereof.
30. 3. A high frequency terminating impedance comprising a section of concentric transmission line, one of whose conductors has a constant resistance per unit length and the other of whose conductors has an effective diameter varying in steps along said section, the ratio of the diameters of successive sections being equal.
35. 4. Apparatus as in claim 3, wherein each of said steps has a length less than one-eighth wave length at the operating frequency of said device.
40. 5. A high frequency terminating impedance comprising a section of concentric transmission line having an outer resistive conductor of uniform inner diameter and uniform resistance per unit length, and an inner conductor whose diameter varies in steps along the length thereof, said steps being selected to provide a constant ratio of successive step diameters along said section.
